Application May 28, 1930. Serial No. 456,681

11 Claims. (Cl. 110—47)

The invention relates to a furnace, as described in the present specification and illustrated in the accompanying drawings that form part of the same.

The invention consists essentially in the novel means employed for automatically manipulating the fuel within the firebox and of the particular manner of delivering it for manipulation, as pointed out in the claims for novelty following a description in detail of an acceptable form of the invention.

The objects of the invention are to increase the efficiency of furnaces in the generation of steam and the production of hot water in heating plants or for other purposes, by so handling the coal or other hard fuel as to maintain its movement from its original condition to its state of ash, and thereby obtain in heating units an equivalent of the maximum properties of the fuel; to promote the combustion of the fuel when it reaches the firebox and thereby facilitate its forward movement, and at the same time effect economy in regard to the quantity of fuel consumed; to eliminate the smoke nuisance, and consequently utilize the full complement of heating gases for the purposes of the furnace; and generally to provide in heating and steam generating equipments a heating element that will produce first class results at a minimum expenditure of money on fuel and labor.

In the drawings, Figure 1 is a perspective view of the interior of the firebox from the rear showing some of the particular features concerned in this invention.

Figure 2 is an elevational detail of a grate bar. Figure 3 is an elevational detail of an eccentric shaft forming part of the grate mechanism and here shown as broken away.

Figure 4 is a plan view of an eccentric box showing the stroke adjusting mechanism.

Figure 5 is a fragmentary detail showing a grate bar and the mountings.

Figure 6 is a perspective view of the furnace front showing the motive power and operating connections.

Figure 7 is a detail of worm and gear connection.

Figure 8 is a sectional detail of the progressive feed members.

Figure 9 is a perspective detail of the spring dog operating plate.

Figure 10 is an elevational view of the furnace front showing the air cooling connections.

Figure 11 is a detail of the hopper agitator in plan.

Figure 12 is a sectional detail of the fire door. Figure 13 is a fragmentary view of the pivoted end of a grate bar and pivot.

Like numerals of reference indicate corresponding parts in the various figures.

Referring to the drawings, the numerals 15 indicate a grate bar of which there are a considerable number, and this grate bar is formed with the jaw 16 extending into one end of the bar in a very slight upward incline and forming the lug 17 a little offset downwardly from the main portion of the bar.

The teeth 18 extend upwardly from the bar towards the other end and at this other end the bar is reduced to form the lug 19 curved downwardly.

The bearing slot 20 extends upwardly from the under edge of the bar inside of the lug 19, thus completing the bar, which rocks from its jaw end.

The eccentric shaft 21 is one of a pair and at one end this shaft terminates in the journal 22 and the square tip 23, and at the other end in the journal 24.

The bar bearings 20 are mounted on the eccentrics 25 and 26, therefore by rotating the shaft 27 the bars are alternately lifted and dropped.

The shaft 27 is one of a pair and these shafts 27 are contained in the jaws 16 of the grate bars so that the shafts 27 and shafts 21 support the grate bars and these grate bars rock on the shafts 27.

These grate bars and the shafts mentioned are supported in a frame 28 secured to a furnace front 29 and the side walls 30 of the frame 28 rise above the grate bars and extend to a short distance inwardly over the lugs 19 as indicated at 31.

The shafts 27 are parallelly arranged in the central portion of the frame and are rigidly secured to the furnace front and to the back wall 32 of the frame 28, and are shown on either side of the central fuel trough 33 which constitutes the path of the fuel that is constantly fed into the furnace and which is intended to rise over the inner ends or jaw ends of the grate bars and be deposited thereon.

The eccentric shafts 21 are journalled at the rear ends in the bearing plates 34 adjustably secured over the slots 35 in the back wall 32 above the tie rods 36 of the frame, which extend between and are secured to the furnace front 29 in the back wall 32 and legs 37.

The grate bars are inclined downwardly from the shafts 27 to the shafts 21 and the latter shafts at their front ends are journalled in the bearings 38, in conformance with the shape of the frame 110

28 and therefore the tendency of the fuel is constant movement, but naturally combustion occurs and incandescence, which results in the deposit of the ash below the grate bars practically from 5 end to end and thereover at the lower side, as it is estimated that the fuel will under the most unfavorable conditions be completely consumed at the lower end of the bars.

10 The trough 33 extends through the furnace front under the fuel hopper 39, which during the operation of the furnace is kept constantly full of fuel.

15 The eccentric shafts 21 are journalled as explained in the bearings 28 in the furnace front and the square tips 23 project through these bearings and furnace front.

20 The gear case 40 is rigidly secured to the furnace front and contains a worm gear 41 fixedly mounted on one of the eccentric shafts 21, there being, as will be readily understood, a similar gear at the other side of the furnace on the other eccentric shaft 21, in fact, while the mechanism is explained on the one side it is obvious that the same mechanism occurs on the outer side in so 25 far as the grate bars and their operating parts are concerned.

30 The worm shaft 42 carries a worm coaxing with the worm gear 41 and is journalled in bearings 43 on the furnace front and extends into and through the casing 44 and at the inner end thereof carries the bevel pinion 45 coaxing with the bevel gear 46 mounted on the driven shaft 47a. The bevel gear 46 naturally drives two pinions, one for one side of the furnace and one for the 35 other side of the furnace, thus the two shafts 21 are kept in constant motion at the speed desired.

40 A motor 48 operates through its shaft 49, a gear set 50 constituting the change speeds from which the crown gear 51 and pinion 52 are driven and consequently the shaft 47. The speed changes are effected by the lever 53 in the customary manner in such mechanisms.

45 The eccentric boxes 54 and 55 are mounted on the driven shaft 47 and have the arcuate end faces registering with the peripheries of the eccentrics 56 and 57 fixedly mounted on the shaft 47 and contained in said boxes.

50 The blocks 58 having the inner arcuate faces 59 slide in the boxes 54 and 55 and are adjusted in said boxes by the wheels 60 and 61 respectively so as to lengthen or shorten the stroke of the eccentrics in the boxes and consequently the travel of the feeding members, through the screw spindles threaded in the back walls of the boxes and 55 swivelly attached to the blocks 58.

60 The eccentrics 56 and 57 may be operated at as many speeds as may be provided in the gearset and also the eccentric shafts 21 and grate bars. In this instance there are three speeds as customary in the driving of motor vehicles, which are usually termed low gear, second gear and high gear.

65 It will be seen that the eccentric shafts and eccentrics may be driven at the rate chosen, the former by the worms and worm wheels and the latter by the driven shaft 47 of the eccentric shafts. At low gear the grate bars will rock very slowly indeed, just keeping up the motion. At second gear or intermediate speed the rocking 70 will be more pronounced, and at high speed the furnace grate throughout will be very well shaken.

75 The portion of the trough extending through the furnace front forms the hopper box 62, in which the plunger 63 operates, this plunger 63

being pivotally connected by the connecting rod 64 to the eccentric box 54 or crank mounted on the driven shaft 47, so that during the rotation of the driven shaft the plunger is intended to reciprocate in the hopper box thereby pushing the fuel dropping down from the hopper into the hopper box 62.

80 The sliding bottom 65 of the trough is slotted at 66 and is connected to the swinging bars 67 through the pivoted dogs 68 the dogs being pivotally secured at 69 to the bottom 65 and pivotally secured to the lugs 70 rigidly secured to the underside of the swinging bars 67, said bottom 65 having the tongue 67a from the bottom thereof.

85 The dogs 68 are formed with the pusher flange 90 71 extending downwardly from the arm 72, which projects forwardly from the hub 73 mounted on the pivots 69 and having the lugs 74 dropped therefrom and pivotally secured to the lugs 70, thus insuring the parallel swinging motion of 95 the bars 67 and bottom 65.

90 The dogs 68 operate in the slots 66 in the bottom 65 so that at the rearward movement of the swinging bars 67 there is a pause before the bottom 65 moves and it is during this pause that the dogs swing on their pivots and disappear in the rearward movement, but in the beginning of the forward movement they swing upwardly and push the fuel, but this forward movement moves the parallel bars and bottom a short distance 100 ahead and this movement continuing progresses the fuel in the trough 33, until the trough is quite full and overflows on to the grate bars on either side.

105 The coupling 75 is pivotally secured to the 110 swinging bars 67 by the pivots 76 at either side and is formed with the body 77 having the tongue slot 78 providing for a limited lost motion in the strokes and at the rear of said body the jaw 79 and pivot 80 joining it to the connecting rod 115 81 extending from the box 55, in which the eccentric operates to move the bottom 65 through the strokes of the bars 67.

110 The bevel gear 82 shown as mounted on the driven shaft 47, coaxing with the bevel gear 83 120 on the shaft 84 which carries at its other end the bevel gear 85 coaxing with the bevel gear 86 mounted on the shaft 87 which may be used for a blower mechanism, not herein shown or described.

125 It may be explained that between the back wall 32 and furnace front 29, the air chambers 88 on either side of the fire box form the bases for the brick work and have the front walls 89 slotted at 90 intermediately under the flat tops 91 130 of said chambers, the said front walls 89 having the bevelled undersides 92 adapted to form the edges 93 to cut clinkers.

130 The chambers 88 extend through the furnace front and the air boxes 94 cover in said passages 135 and are fixedly secured to the front and have the inlets 95 connected by the pipes 96 to a supply of air preferably above atmospheric pressure or supplied by a blower under a forced draft system.

140 The flexible metal fireproof tubings 97 and 98 extend from the outlets 99 of the boxes 94 to the fire doors 100 and 101 and particularly to the inlets 102 and 103 entering the chambers 104 respectively which are situated between the perforated linings 105 and the dished doors.

145 The hopper 39 in use is sometimes bridged by screenings thereby holding up the feed, consequently it is desirable to agitate the contents of the hopper and this is done by introducing the 150

poker 106 into the slot 107 in the hopper wall towards the lower end and this poker 106 forms an arm from the eccentric strap 108 encircling the eccentric 109 mounted on the driven shaft 47.

5 The agitation by the wagging poker keeps the fuel from clogging up the hopper and insures regularity in the feed.

The eccentric shafts 21 journalled in the plates 34 are adjusted in the slots 35 by the eccentrics 10 96 mounted on the tie rods 36 and supporting said plates.

In the operation of this invention, the hopper is filled with coal and kept filled by hand or by any other conveyer mechanism, and this coal 15 drops into the hopper box and from there is pushed forward by the plunger as has already been explained, and kept in its forward movement until it progresses through into the trough between the sides of the grates formed by the 20 grate bars.

This trough is filled and overflows on to the grate bars, which are lifting and dropping alternately, this being accomplished by the rotation of the eccentric shafts, each eccentric on these 25 shafts being the reverse of the adjacent eccentric, so that the grate bars lift and fall in sequence respectively, that is to say, one lifts and the next one falls and the next one lifts and the next one after falls resulting in a continuous agitation and 30 consequently the entire absence of clinkers.

The ash falls through to the ash pit or it may be fed by a conveyer from the ends or in any suitable manner, the salient feature of the invention being the continuous movement imparted to the 35 fuel from the time it is pushed in by the plunger until it eventually reaches a state of ash, of course by this means a very hot fire may be maintained though in the slower movement of the feed and of the agitation the strength of the fire is considerably reduced and these changes in speeds 40 may be made by the variable speed mechanism by means of a lever attached thereto in very much the same way that speed changes are made in vehicular traffic.

45 The outstanding advantages of course are the promotion of combustion, the absence of clinkers and the steady maintenance of the feed.

What I claim is:—

1. In self stoking furnaces, a furnace front, a 50 firebox frame rigidly secured to said front, a motor having its shaft operatively connected to a driven shaft, a mechanical stoker driving the fuel into the center of the firebox and operatively connected to said driven shaft, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on said eccentrics at their outer ends, means connecting said stoker to said driven shaft and means connecting said eccentrics to said driven shaft.

65 2. In self stoking furnaces, a furnace front having shaft bearings, a hopper and motive power equipment connected thereto, a firebox frame rigidly secured to said front, a motor having its shaft operatively connected to a driven shaft, a 70 mechanical stoker driving the fuel into the center of the firebox and operatively connected to said driven shaft, a central fuel trough in the firebox, pivot shafts rigidly secured to the furnace front and firebox frame on either side of said trough, eccentric shafts having alternating ec-

centrics and journalled in said front and said frame adjacent to the side walls of said frame, grate bars pivotally mounted on said pivot shafts at their inner ends and bearing on said eccentrics at their outer ends, means connecting said stoker to said driven shaft, and means connecting said eccentrics to said driven shaft.

80 3. In self stoking furnaces, a furnace front, a firebox frame having side walls overhanging the grate, a back wall standing on legs and tie rods securing the back wall and legs to the front, a motor having its shaft operatively connected to a driven shaft, a mechanical stoker driving the fuel into the center of the firebox and operatively connected to said driven shaft, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting said stoker to said driven shaft and means connecting said eccentrics to said driven shaft.

85 4. In self stoking furnaces, a furnace front, a firebox frame rigidly secured to said front, a motive equipment having the motor shaft extend into change gears and a driven shaft operatively connected to the gear set giving the changes in speed in the several movements, a mechanical stoker driving the fuel into the center of the firebox and operatively connected to said driven shaft, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting said stoker to said driven shaft, and means connecting said eccentrics to said driven shaft.

90 5. In self stoking furnaces, a furnace front, a firebox frame rigidly secured to said front, a motor and a variable speed mechanism connected to a driven shaft operating the grates and the fuel feeding mechanism, a mechanical stoker driving the fuel into the center of the firebox and operatively connected to said driven shaft, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting said stoker to said driven shaft, and means connecting said eccentrics to said driven shaft.

95 6. In self stoking furnaces, a furnace front, a firebox frame rigidly secured to said front, a motor having its shaft operatively connected to a driven shaft, a mechanical stoker having a plunger operating at the lower end of a hopper and connected to an eccentric on said driven shaft and driving the fuel into the firebox, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on

- said pivot shafts at their inner ends and bearing on eccentrics at their outer ends, means connecting said stoker to said driven shaft, and means connecting said eccentrics to said driven shaft.
- 5 7. In self stoking furnaces, a furnace front, a firebox frame rigidly secured to said front, a motor having its shaft operatively connected to a driven shaft, a mechanical stoker having a reciprocating plunger and a sliding bottom having 10 disappearing dogs reciprocally operating in the center of the firebox, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting 15 said stoker to said driven shaft, and means connecting said eccentrics to said driven shaft.
- 10 8. In self stoking furnaces, a furnace front, a firebox frame rigidly secured to said front, a motor having its shaft operatively connected to a driven shaft, variable speed mechanism introduced between said motor and driven shaft, a mechanical stoker having a plunger and a carrier plate operating at varying speeds controlled by said variable speed mechanism, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting said stoker to said driven shaft, and means connecting 20 said eccentrics to said driven shaft.
- 20 9. In self stoking furnaces, a furnace front, a firebox frame rigidly secured to said front, a motor having its shaft operatively connected to a driven shaft, a mechanical stoker driving the fuel into the center of the firebox and operatively connected to said driven shaft. a central fuel 25 trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting said stoker to said driven shaft, worm wheels having casings secured to the furnace front, worm shafts and worms having casings secured to the furnace front and forming bearings, and gear mechanism connecting said worm shaft to the said driven 30 shaft.
- 30 10. In self stoking furnaces, a furnace front, a firebox frame rigidly secured to said front, a motor having its shaft operatively connected to a driven shaft, a mechanical stoker having a plunger and a carrier plate operating at varying speeds controlled by said variable speed mechanism, a central fuel trough in the firebox, pivot shafts rigidly secured to the furnace front and firebox frame on either side of said trough, eccentric shafts having alternating eccentrics and journalled in said front and said frame adjacent to the side walls of said frame, grate bars pivotally mounted on said pivot shafts at their inner ends and bearing on eccentrics at their outer ends, means connecting said stoker to said driven shaft, worm wheels having casings secured to the furnace front, worm shafts and worms having casings secured to the furnace front and forming bearings, and gear mechanism connecting said worm shaft to the said driven 35 shaft.
- 35 11. In a self stoking furnace, a hopper, a trough having a sliding bottom and pushers therein, a plunger reciprocating under said hopper, a driven shaft, eccentrics mounted thereon, eccentric boxes forming straps and having connecting rods therefrom, arcuate adjusting blocks in said boxes having adjusting screws, parallel swinging bars connected to said pushers and bottom and a coupling having a tongue slot receiving a tongue from 40 said bottom having a limited movement in the slot, said coupling joining a connecting rod and said parallel bars.
